United States Patent Office

Des. 188,195
Patented June 14, 1960

188,195

TRAY TABLE RACK

Robert H. Dunbar, 455 Virginia Ave., Pasadena, Calif.

Filed Oct. 29, 1958, Ser. No. 53,204

Term of patent 14 years

(Cl. D33—3)

Fig. 1 is a perspective view of the tray table rack of the invention;

Fig. 2 is a side elevational view of the rack; and

Fig. 3 is a front elevational view.

I claim:

The ornamental design for a tray table rack, as shown.
